GAS BURNER

Herbert R. Palmer, Shaker Village, Ohio, assignor
of one-half to Thomas H. Tubman, Akron,
Ohio

Application February 6, 1934, Serial No. 710,024

9 Claims. (Cl. 158—117)

This invention relating to improvements in gas burners and more particularly such burners adapted for use with cooking stoves, will be readily understood from the following description, taken in connection with the accompanying drawing, in which:

Figure 1 is a plan view of the improved burner;
Figure 2 is a longitudinal sectional view on the line 2—2 of Figure 1;

Figure 3 is a section on the line 3—3 of Figure 2; and

Figure 4 is a longitudinal sectional view through the air shutter shown detached from the burner.

Referring more particularly to the drawing 5 denotes the burner, comprising the usual mixing

20 tube 6 to the outer end of which gas is supplied from a manifold not shown, connected in any suitable manner with the opening 7, in cap 8.

An adjustable shutter 9 formed of thin resilient

25 metal, and snugly sleeved upon the mixing tube regulates the flow of air drawn into the tube 6, through side openings 10, by the inflowing gas.

The opposite ends of the shutter 9 are bent inwardly and slotted as at 11 to form tongues 12

25 adapted to resiliently grip the mixing tube and hold the shutter in any desired adjusted position.

The shutter can be slid longitudinally or it can be rotated to bring the slots 11 into or out of

30 register with the side air openings 10, thus permitting very fine adjustment. However, the

frictional engagement of the tongues 12 with the mixing tube precludes accidental movement

35 of the shutter. By locating the air openings in the sides of the tube, instead of in the cap 8

as usual, the air is drawn in from all sides with a very desirable swirling action. The inner wall

35 of the mixing tube is gradually contracted and then expanded just in advance of the air openings 10, as at 13, thus insuring a Venturi-like

40 action.

The inner end of the mixing tube is enlarged at its outer end into a substantially bowl shaped

45 burner portion 14 comprising an integral up-standing tube or inner wall 15 concentrically dis-

posed with respect to and spaced from the outer

45 wall 16 thereof, the annular space between the

two walls constituting a distributing chamber 17.

The opening or passage 18 through the tube 15

50 insures an ample supply of secondary air. The

outer wall 16 of the burner is fluted to increase

the flame area and intensity of the flame with-

55 out a corresponding increase in gas consumption.

The distributing chamber 17 is partially closed

55 at its upper end by a burner head or plate 19

which is supported in slightly spaced relation

to and directly above the top edges of the walls

55 15 and 16 by means of threaded bolts 20 fixedly

55 mounted in bosses 21 formed in the bowl shaped

burner portion 14. Plate 19 is provided with a

60 round centrally disposed aperture 22 which coin-

cides in size and registers with the opening 18, and the outer end of the plate is corrugated or fluted to correspond to and register with the corrugations in the outer wall 16, or in other words the peripheral edge of plate 19 is substantially flush with the outer face of wall 16, when the parts are assembled. An unobstructed circular inner flame outlet or opening 23 and an unobstructed outer irregular flame outlet or opening 24 is thus provided. A baffle member 10

25 located in the air opening or passage 18, and

preferably supported from plate 19 by means of

arms 26, prevents a too free flow of air to the

flame openings.

The action of the flames is as follows: the inner ring like flame issuing from the inner ring shaped slot 23 between the top of the inner wall 15 of burner 14 and the inner edge of axially perforated plate 19 heats the central area of a cooking utensil supported in proper distance from the burner, and the outer flame issuing from the irregular slot 24 between the top of the outer wall 16 and the outer edge of plate 19 heats the substantially ring shaped area of said utensil adjacent to said central area. The inner flame 25 is of uniform character throughout, however, due to the irregular configuration of the outer wall 16 in cooperation with the inner tubular wall 15 of the burner, the flame issuing through the outer burner passage 24 varies in intensity at 30 more or less uniformly spaced areas throughout the entire circumferential area thereof. This peculiar action results from the fact that areas differing from each other in size and configuration are formed between the inner and outer 35 walls 15 and 16 and within the chamber 17. As the portions of wall 16 constituting the outer wall portions of these differently sized areas are of varying angularity with respect to the axis of the burner, the gas and air mixture at certain 40 points or areas will be discharged out through the irregularly shaped passage 24 in partly opposing or converging directions with respect to adjacent areas. The intensity of the flame is greatly increased at these converging points and 45 it has been found that a maximum of heating efficiency can thus be obtained with a minimum consumption of fuel. According to this arrangement and construction of parts it is also possible to obtain an exceptionally large flame area with 50 a very small burner.

The bolts 20 project upwardly through openings 27 in the plate 19, and the latter is adjustably supported on the bolts by means of nuts 28 threaded on their threaded outer 55 ends, the plate being provided with upwardly and inwardly extending fingers 29 engaging the top of the nuts. It will thus be seen that the plate can be conveniently elevated or lowered and the size of opening 24 increased or decreased 60

by merely turning the nuts 28 in an appropriate direction. The nuts 28 are provided with integral caps or heads 30 which prevent grease and other foreign matter from reaching the threads of the nuts or bolts. These heads are preferably slotted to permit use of a screw driver or the like in turning the nuts.

A downwardly and outwardly inclined annular apron-like member 31 formed with a large central opening 32, encircles the wall 16 in slightly spaced relation thereto and slightly below the top thereof and keeps the cold air from the burner. The member 31 is supported from the plate 19 by means of arms 33.

97 While my improved burner is particularly adapted for use with cooking stoves, it will be understood that it can also be used in furnaces and hot water heaters.

Having thus described my invention:

98 What I claim is:

99 1. A gas burner comprising a body having an opening and a substantially ring shaped mixing chamber open at its top, the inner cylindrical wall of said chamber forming an open ended passage having its upper open end horizontally aligned with the open top of said chamber and the outer wall of said chamber being fluted to provide an outlet opening of varying area at the top of said chamber, a plate shaped to fit the open top of said chamber adjustably mounted slightly above the open top of said body to provide substantially concentric outlet passages from said chamber to the open atmosphere, and means adapted to shift said plate vertically with respect to said body for varying the width of said outlet passages.

100 2. A gas burner comprising a body having an open-top and a substantially ring-shaped mixing chamber having the tops of its walls horizontally aligned, the inner cylindrical wall of said chamber forming an open ended passage and the outer wall of said chamber being fluted to provide an outlet opening of varying area at the top of said chamber, a flat centrally perforated plate shaped to fit and close the open top of said chamber adjustably mounted slightly above the open top of said body to provide substantially concentric outlet passages from said chamber to the open atmosphere, means adapted to shift said plate vertically with respect to said body for varying the width of said concentric outlet passages and means within said open ended passage and supported by said plate to partly obstruct a flow of air through said open ended passage.

101 3. A gas burner comprising a body having an open-top and a substantially ring-shaped mixing chamber having the tops of its walls arranged in the same horizontal plane, the inner wall of said chamber being cylindrical and the outer wall of said chamber being fluted to provide an outlet opening of varying area at the top of said chamber, a flat axially perforated plate having the same irregular configuration as said outlet opening mounted slightly above the open top of said body to provide two substantially concentric, narrow outlet passages for the gas and air mixture in said mixing chamber, and means adapted to shift said plate vertically with respect to said body for varying the width of said two outlet passages.

102 4. A gas burner comprising a bowl shaped

body having an open top, a fluted outer wall and a cylindrical inner wall having its top horizontally aligned with said outer wall and being axially aligned with and spaced from said outer wall to provide a substantially ring-shaped mixing chamber enclosing an axial passage through said body, a flat axially perforated plate having the irregular configuration of said chamber and mounted slightly above the open top thereof in alignment with the outer and inner walls to 10 provide two substantially concentric narrow outlet passages for the gas and air mixture in said mixing chamber, and means extended through said mixing chamber adapted to shift said plate vertically with respect to said body 15 for varying the width of said two outlet passages.

103 5. A gas burner comprising a bowl shaped body having an open top, a fluted outer wall and a cylindrical inner wall having their tops 20 horizontally aligned with each other, said inner wall being axially aligned with and spaced from said outer wall to provide a substantially ring-shaped mixing chamber enclosing an axial passage through said body, and a flat axially per- 25 forated plate having the irregular configuration of said chamber and mounted slightly above the open top thereof in alignment with the inner and outer walls to provide two substantially concentric narrow outlet passages of equal width 30 adjacent the inner and outer walls of said chamber.

104 6. A gas burner as described in claim 4, wherein in said adjusting means for said disk include a plurality of symmetrically arranged threaded posts, and rotatable means threadedly connected with the upper ends of said posts and wherein said plate is provided with means for coupling said plate with said rotatable means.

105 7. In a gas burner embodying a burner body 40 and a burner manifold, a venturi within said manifold, air openings circumferentially arranged in the wall of said manifold adjacent to said venturi and a sleeve member mounted on said manifold for longitudinal and rotatable 45 movement, said member having slotted, yielding end portions yieldingly engaged with said manifold to hold said sleeve in its adjusted position.

106 8. A gas burner comprising a substantially bowl shaped body having an open top and a substantially ring shaped mixing chamber having the tops of its walls arranged in the same horizontal plane, a flat axially perforated plate having the configuration of said mixing chamber mounted slightly above the open top of said 55 body to provide substantially concentric narrow inner and outer unobstructed outlet passages for the gas and air mixture discharged from said mixing chamber, and means for adjusting said plate to increase or decrease the capacity of 60 said passages.

107 9. A gas burner as described in claim 4, wherein in said means extended through said mixing chamber consists of a plurality of symmetrically arranged threaded posts and nuts threadedly connected with the upper ends of said posts and wherein said plate is provided with means for coupling said plate with said nuts and said nuts include caps to protect the threads of the nuts and posts.
